HENRY A. WISE WOOD, OF NEW YORK, N. Y., ASSIGNOR TO WOOD NEWSPAPER MACHINERY CORPORATION, OF NEW YORK, N. Y., A CORPORATION OF VIRGINIA

IMPALING PIN

Application filed September 27, 1928, Serial No. 308,687. Renewed December 4, 1930.

This invention relates to the impaling pins of a folding cylinder.

The principal objects of the invention are to provide a folding cylinder with impaling pins which at the moment when the paper is started on its forward side to move in a direction contrary to the direction of rotation of the cylinder, these pins will move a short distance with it, thereby avoiding irregular tearing of the paper and permitting of increasing the speed of the folding couple and to provide a construction in which the lateral movement of the pins is performed with very simple mechanism and they are restored to normal condition automatically and instantaneously.

Other objects and advantages of the invention will appear hereinafter.

Reference is to be had to the accompanying drawings in which

Fig. 1 is an end view of a folding couple showing the folding cylinder in section illustrating a preferred embodiment of this invention;

Fig. 2 is a similar view showing the parts in the position in which the folding blade is just starting to tuck the fold into the folding rolls and the forward edge of the product is moving backwardly and the pins yielding;

Fig. 3 is a side view of a part of the cylinder;

Fig. 4 is a sectional view on the line 4—4 of Fig. 1, and

Fig. 5 is a view similar to Fig. 2 showing a modification.

It is desirable to withdraw the impaling pins into the folding cylinder of a printing press in as short a time as possible while the paper is being introduced between the folding rollers. The speed of the entire folding machine is seriously limited by the fact that these pins have to be operated by a cam and the higher the speed the steeper the cam. When the cam is changed so as to permit speeding up, it brings about a disadvantage which is detrimental to correct folding. As the folded product has a great number of pages the slow withdrawal of the impaling pins will cause loss of control of the outside pages before the inside pages

are released by withdrawal of the pins therefrom. At the moment of folding the forward edge of the sheet is made to move in a direction opposite to the direction of rotation of the cylinder. If the pins are left in, just at this instant, large gashes or rips are necessarily left in the forward edge of the paper unless the operator is willing to sacrifice the control of the paper by withdrawing the pins very suddenly.

In order to overcome this difficulty and permit high speeds I give the pins a backward motion, that is, a motion in the direction in which the forward edge of the sheet starts to travel when being tucked in the folding rolls. During this withdrawing action the pins move backwardly with the paper so that they have time to be withdrawn without pulling through the edge of the paper.

Referring now to the first four figures it will be seen that the folding cylinder 10 is provided with the usual folding blades 11, the means for operating them not being shown, as any ordinary means can be used with this invention.

The usual shafts 12 are employed which are turned by a cam, not shown. They are provided with arms 13 which project into slots 14 in the impaling pins 15. These pins are mounted to slide in bars 16 which are in turn pivoted to swing on pivot studs 17 located at their rear ends. Each bar is provided with a spring 18 engaging in a notch therein and tending to push the bar back against a surface 19 with which the folding cylinder is provided, which is close to the cutting rubbers 20.

It will be seen that, irrespective of the position of the bar 16 about its pivot, the arm 13 can operate the pin in the usual way and that, in the normal position, as shown in Fig. 1, the impaling pins project through adjacent to the cutting rubbers.

By reference to Fig. 2, however, it will be seen that when the operation is substantially finished and the impaling pins have to hold the sheet at the moment when the folding blade 11 starts to fold the sheet and push it through the folding rolls 22, the sheet itself is strong enough to pull the impaling pins back against their springs 18,

as indicated in this figure. This gives a dwell to the impaling pins and permits them to be withdrawn from the paper without stripping the paper from the pins and causing slits clear through to the edge of the paper. Yet control of the paper is retained as long as is possible and up until the paper is within the control of the folding rolls 22. This permits the use of a slower cam and a higher speed of the press and improves the control of the paper on the folding cylinder. As soon as the pins are withdrawn the springs force them back into the position shown in Fig. 1.

15 It is not necessary to provide a yielding means for this purpose and I have shown in Fig. 5, an arrangement by which an extra stationary cam 25 is employed operating a roll 26 which is on an arm 27 connected with the rod 16 or with the stud 17 on which it is pivoted. This cam is so designed and timed that when the folding blade 11 swings about it will be just ready to draw back the impaling pins 15. In the position shown in 20 Fig. 5 this is just about to take place as will be obvious. This provides a positive control of the pin and otherwise secures the same results as above specified.

Although I have illustrated and described 30 only two forms of the invention I am aware of the fact that other modifications can be made therein by any person skilled in the art without departing from the scope of the invention as expressed in the claims. Therefore, I do not wish to be limited in this respect but what I do claim is:—

1. The combination with a folding cylinder provided with reciprocable impaling pins; of a folding blade, of means whereby 40 when the forward edge of the paper is drawn back on the surface of the cylinder by the projection of the folding blade, the impaling pins will move rearwardly on the cylinder a short distance in the direction in which said paper is being drawn back.

2. The combination with a folding cylinder having impaling pins carried thereby, and folding blades, of means whereby when the folding blade is projected to form a fold 50 in a sheet carried by the cylinder, and thus draw the paper in advance of the folding blade back on the surface of the cylinder, the impaling pins will move backwardly with the end of the sheet in the direction in which the paper is being drawn back and means for then withdrawing the pins.

3. The combination with a folding cylinder, of pivoted bars carried thereby, impaling pins reciprocable within said bars and 60 springs located behind said bars, whereby the impaling pins and bars can be moved about the pivot and will be restored by the springs to normal position.

4. The combination with a folding cylinder, of pivoted bars carried thereby, im-

paling pins mounted to reciprocate in said bars, a cam in fixed position and an arm controlled by said cam for swinging the bars backwardly when the paper on the cylinder is being folded.

5. In a folding mechanism, the combination with a sheet-carrying cylinder, and sheet impaling pins thereon adapted to hold the sheet upon the surface of said cylinder, of means for giving said pins a rocking motion 70 in the plane of rotation of said cylinder. 75

6. In a folding mechanism, the combination with a sheet carrying cylinder, of sheet impaling pins pivotally mounted thereon and means for moving the pins rearwardly on the cylinder for projecting into the paper at the time when the sheet is being removed from the cylinder. 80

7. In a folding mechanism, the combination with a sheet-carrying folding cylinder, a rotating folding blade carried thereby, and impaling pins adapted to hold the sheet upon the said cylinder, of means for rocking the said pins in a rearward direction as the sheet is folded off the said cylinder. 85 90

8. In a folding mechanism, the combination with a sheet-carrying folding cylinder, a rotating folding blade carried thereby, and impaling pins adapted to hold the sheet upon the said cylinder, of means for rocking the said pins in a rearward direction as the sheet is folded off the said cylinder, and for thereafter returning the pins to their original position. 95

9. The combination of a folding cylinder, 100 a folding blade adapted to fold off the sheet carried thereby, impaling pins mounted to rock rearwardly as the folding blade engages the said sheet, and means other than the sheet for controlling the rocking action of the pins. 105

10. In combination a folding cylinder, a folding blade carried thereby, sheet carrying impaling pins arranged to move rearwardly as the said blade acts to fold off the sheet, and positively operated means for restoring 110 the pins to their forward position.

11. In combination a folding cylinder, a folding blade carried thereby, sheet carrying impaling pins arranged to move rearwardly as the said blade acts to fold off the sheet, and positively operated means for controlling the rate of speed at which the pins move rearwardly with the sheet. 115

12. In combination a folding cylinder, a folding blade carried thereby, sheet carrying impaling pins arranged to move rearwardly as the said blade acts to fold off the sheet, and positively operated means for controlling the rate of speed at which the pins move rearwardly with the sheet, and return to their 120 forward position. 125

13. In combination a folding cylinder, a folding blade carried thereby, sheet carrying impaling pins adapted to move rearwardly in order to release the sheet for folding, and 130

means for returning the pins to their forward position at a predetermined rate of speed.

14. In combination a folding cylinder, a folding blade carried thereby and sheet carrying impaling pins adapted to move rearwardly with the sheet at a predetermined rate of speed as the said blade draws it from the cylinder.

15. In combination with a folding cylinder and its folding blade, of a rock shaft and sheet carrying pins mounted upon the said shaft to rock to and fro in the plane of rotation of the said cylinder and positive means for controlling the rearwardly rocking motion of the said pins.

16. In combination with a folding cylinder and its folding blade, of a rock shaft carrying pins adapted to rock to and fro in the direction of travel of the said sheet, and

20 means for rocking the said shaft to and fro.

17. In combination with a folding cylinder and its folding blade, of a rock shaft upon which are mounted sheet carrying pins and resilient means permitting the sheet as it is

25 folded off to draw the pins in a rearwardly direction and positively operating means for

returning the pins to their original position

after they have been released from the sheet.

20 In testimony whereof I have hereunto af-

fixed my signature.

HENRY A. WISE WOOD.
